UNITED STATES PATENT OFFICE.

HUBERT G. FLETCHER, OF LONOKE, ARKANSAS.

STEAM INJECTOR FOR INTERNAL-COMBUSTION ENGINES.

Application filed February 28, 1924. Serial No. 695,282.

To all whom it may concern:

Be it known that I, HUBERT G. FLETCHER, a citizen of the United States, residing at Lonoke, in the county of Lonoke and State 5 of Arkansas, have invented certain new and useful Improvements in Steam Injectors for Internal-Combustion Engines, of which the following is a specification.

This invention relates to steam injectors 10 for the carbureters of internal combustion engines.

It is a well known fact that the injection of heated air, steam, or vapor to mix with the charge from a carbureter to an internal 15 combustion engine enhances the explosive effect or power derived from the carbureted mixture; many systems and appliances have been provided for feeding air, steam, or vapor for this purpose.

20 My object is to provide a novel system or appliance by which the quantity of moisture in the vapor or steam derived from the radiator of the engine is reduced to the point where the vapor mixes most effectively with 25 the carbureted mixture in the mixing chamber of the carbureter thus forming a more highly volatile, explosive, and powerful mixture or charge to be sent to the engine than ordinarily which not only enables the 30 engine to derive more power from the mixture but also economizes in the gasoline consumption.

A further object is the provision of a 35 novel system or appliance of the character set forth by which, when the engine is first started, or turned over, a certain quantity of moisture will be drawn into the mixing chamber of the carbureter to blend with the charge and to assist in starting, even before 40 the temperature of the water in the cooling system of the engine has been raised sufficiently to provide the vapor which my improved system superheats and furnishes to the carbureter after the engine has started.

45 A practical embodiment of my invention takes the vapor or steam, as the case may be, from the radiator of the engine, treats it in a vacuum tank, superheats, so to speak, the vapor or steam, and passes the dry, or relatively dry, steam to the mixing chamber of the carbureter. The vacuum tank in my invention constitutes an important part or feature thereof because it provides for the 50 expansion of the water vapor derived from

the radiator, causes a precipitation of water 55 from the vapor and insures the delivery from the vacuum tank of a more volatile and drier form of vapor or steam. The expansion and refining of the vapor in the vacuum tank eliminates such a quantity of moisture or water therefrom that the dried, or relatively dried, vapor passing from the vacuum tank is in a condition enabling it to mix most effectively with the charge in the mixing chamber of the carbureter. The vacuum 60 tank also acts as an equalizer or stabilizer of the quantity of moisture delivered to the carbureter mixing chamber and thereby insures an even or uniform flow of moisture and a resultant even and uniform flow of 70 power from the engine. The vacuum tank by permitting the passage to the carbureter only of relatively light, hot, live steam, prevents the lowering of the temperature of the heating chamber of the heater which I utilize to dry the vapor or steam before it is finally passed to the carbureter; this insures a better mixture in the carbureter.

75 While the invention will operate without the use of a heater, I have found that it is preferable to employ a heater, interposed in the feed line from the vacuum tank to the carbureter for the purpose of drying the vapor or steam; this heater may be conveniently attached to the exhaust manifold of 80 the engine and it may assume the form of a "stove."

85 Another feature of the invention which is of peculiar advantage, is the provision of a trap or seal in the pipe line connecting the vacuum tank to the radiator for the purpose of preventing the vacuum in the tank from being lowered by the admission of atmospheric pressure; this seal or trap also may be provided with a pet cock to enable draining 90 to be had to prevent freezing in winter.

The vacuum tank is preferably provided with an automatic water relief float so that the precipitated water may drain when it reaches a predetermined level.

100 It is to be understood that the "vacuum tank" forming a part of the present invention is an entirely separate and distinct thing from what is known as the usual "vacuum tank" of an internal combustion engine, such last named tank being used for the gasoline feed.

I am aware that modifications may be

resorted to in carrying out the invention without departing from the essential principles thereof and I reserve the right to modify the invention within the spirit and scope thereof.

In the accompanying drawings:

Figure 1 is a side elevation showing the invention applied to an automobile engine.

Fig. 2 is an enlarged vertical section, 10 partly in full lines, of the vacuum tank.

Fig. 3 is a detail section of the heater.

Fig. 4 is a front elevation thereof; and

Fig. 5 is an end elevation showing the manner in which the heater is secured to the 15 exhaust pipe or manifold.

The engine appears at 1 and the radiator at 2. The carburetor 3 may be of any construction. The exhaust pipe and manifold are shown at 4. I have illustrated the 20 invention in connection with an automobile engine, but it will be understood that the appliance or system may be used with any internal combustion engine whether stationary or mounted on a land or water vehicle.

25 The radiator overflow pipe is shown at 5. Preferably, although not necessarily, the system is arranged to receive the vapor or steam from pipe 5 but it will be understood that the vapor or steam could be derived 30 from the extreme upper part of the radiator, above the water line.

The improved vacuum tank employed in connection with the invention appears at 6 and is shown in detail in Fig. 2. The upper 35 part of this tank is connected by a pipe or tube 7 to the overflow pipe 5 or the extreme upper part of the radiator. For the purpose of providing a trap or seal to catch the water of condensation, the pipe 7 has a bend 40 or elbow 8 which is provided with a pet cock 9 so that it may be drained in winter to prevent freezing. The trap or elbow 8 maintains the proper vacuum in the tank 6 as the water in said trap or seal tends to 45 prevent the atmosphere from having access to the tank 6 through the pipe 7.

The vacuum tank 6 is preferably provided with a splash wire screen or partition 10 in its upper part which prevents excessive 50 splash of the water, precipitated from the vapor or steam, that collects in the bottom of the tank.

The bottom of the tank is provided with a valve seat 11 to which is connected a tube 55 or pipe 12 by which drainage, under the control of a float 13, is permitted.

The float 13 is carried by a stem 14 and carries a valve 15 which is adapted to rest on seat 11. The stem 14 is guided in a bearing 16 on a frame 17 which is secured to the bottom of the tank 6. A coil spring 19, surrounding stem 14 and interposed between float 13 and frame 17, normally keeps the valve 15 tightly closed against the seat 11.

65 When, however, the accumulation of pre-

cipitated water in the bottom of tank 6 reaches a certain level, the float rises and lets off the excess and then closes. The purpose of maintaining water in the tank 6 is to afford a certain degree of moisture which 70 may be drawn into the carburetor when the engine is first turned over or started, to facilitate starting and increase the power at that time.

The vapor or steam entering the vacuum tank 6 through the pipe 7 may be delivered directly to the carburetor 3 but to obtain the best results it is preferable to heat or dry 75 the vapor or steam. To that end, there is provided a heater 19' which may be of any preferred form, said heater being attached in any suitable manner to the exhaust manifold 4 or pipe as shown in Fig. 1.

The vapor or steam is conducted by a pipe 20 from the top of the tank 6 to the heater 19' and after passing through said heater it enters a pipe 21 which delivers it to the carburetor 3.

A practical form of heater 19'' is that shown in detail in Figs. 3, 4 and 5, said heater having an inlet nipple 22, cells or chambers 23, and an outlet nipple 24 and being curved to fit the manifold or the exhaust pipe. A suitable clamp 25 secures the heater in position.

It will be understood that the suction of the engine creates the vacuum in tank 6 and causes the vapor or steam to be drawn into the tank through the pipe 7 but as the seal 8 is provided the lowering of the vacuum due to access of the atmosphere is minimized. The vapor or steam drawn into the tank 6 carries a very considerable percentage of moisture. The vacuum existing in tank 6 causes an expansion of the vapor or steam which results in precipitation of a very considerable amount of the water in the vapor or steam and this collects in the bottom of the tank but is relieved by the rising of float 13 in the manner previously 100 set forth. The suction of the engine draws the dried vapor or steam into the mixing chamber of the carburetor where it blends with the charge to bring about effects previously described. By the provision of the heater 19 the steam or vapor is rendered even drier than were said heater not used, with resultant volatility of the vapor or steam, and thus superior results are obtained in the carbureted charge.

When the engine is cold, the first cranks 105 or turnings over will result in moisture laden air being drawn from the tank 6 into the engine cylinders to assist in operation, even before the temperature of the water in the radiator is sufficiently high to give off vapor. As soon as vapor begins to enter the system, increased power in the engine 115 will result.

I claim:

1. In a steam injector for internal combustion engines, the combination with a vacuum tank independent of the usual gasoline vacuum tank, of means for supplying vapor or steam from the engine radiator to said tank, and a conduit for delivering vapor or steam from said vacuum tank to mix with the charge for the engine.
2. In a steam injector for internal combustion engines, the combination with a vacuum tank independent of the usual gasoline vacuum tank, of means for supplying vapor or steam from the engine radiator to said tank, and a conduit for delivering vapor or steam from said vacuum tank to mix with the charge for the engine, said conduit enabling
3. In a steam injector for internal combustion engines, the combination with a vacuum tank independent of the usual gasoline vacuum tank, of a pipe for supplying vapor or steam from the engine radiator to said tank, said pipe being provided with a water seal or trap to minimize the admission of air to the vacuum tank, whereby the vacuum is maintained in said tank, and a conduit for delivering vapor or steam from said vacuum tank to mix with the charge for the engine.

In testimony whereof I affix my signature.
HUBERT G. FLETCHER.
